Des. 188,000
Patented May 24, 1960

188,000

SUPPORT FOR A FLASHLIGHT OR SIMILAR ARTICLE

Jesse P. Shanok and Victor Shanok, both of 863 65th St., Brooklyn 20, N.Y.

Filed May 8, 1959, Ser. No. 55,848

Term of patent 14 years

(Cl. D48—24)

FIG.1

Figure 1 is a side elevational view of a support for a flashlight or similar article showing our new design in raised position with a flashlight shown in dotted lines for illustrative purposes only;

We claim:

The ornamental design for a support for a flashlight or similar article, substantially as shown and described.
